(57) **CLAIM**

The ornamental design for a record player, as shown and described.

DESCRIPTION

FIG. 1 is a front, top perspective view of a record player, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view of the record player, shown in an alternative position.

The broken lines in the figures illustrate portions of the record player that form no part of the claimed design.
